UNITED STATES PATENT OFFICE.

CLARENCE ALEXANDER BODDIE, OF BOSTON, MASSACHUSETTS.

ALTERNATING-CURRENT MAXIMUM-DEMAND WATTMETER.

1,206,772.

Specification of Letters Patent. Patented Nov. 28, 1916.

Application filed March 30, 1912. Serial No. 687,395.

To all whom it may concern:

Be it known that I, CLARENCE ALEXANDER BODDIE, a citizen of the United States, residing at Boston, in the county of Suffolk and State of Massachusetts, have invented certain new and useful Improvements in Alternating-Current Maximum-Demand Wattmeters, of which the following is a specification.

10 The present invention relates to the type of wattmeters known as the maximum-demand instruments.

The practical demand for instruments which will record the maximum amount of 15 power used at the period of greatest demand in a given period is a large one, and the instruments now on the market are in many ways unsatisfactory. The most usual type is that in which a maximum demand attachment is used in conjunction with a wattmeter of recognized type and is provided with a controlling or time element consisting of a clock mechanism.

20 The principal objections to this type of maximum-demand meters are the necessity of winding the clock mechanism at stated intervals to place the attachment in condition for registering the maximum power values and the large dimensions of a case 25 that will contain the clock mechanism and the wattmeter or the alternative of mounting the clock mechanism and the wattmeter in separate cases. And, it may be added, recording instruments of this character having multiplied and complicated parts are 30 not reliable in constant and extended use.

The object of this invention is to construct 35 a maximum-demand wattmeter which will obviate the objectionable features above set 40 forth, as well as other objections which may be raised against instruments of this class. Thus, the present invention comprises an attachment which is embodied in a wattmeter of the integrating type to be mounted 45 in the case of any of the well known and standard makes of wattmeters without enlarging to any extent, if at all, the dimensions of said case. In carrying out the 50 above construction, the wattmeter mechanism, or what will be termed the main mechanism, is so connected to the maximum-demand mechanism, or as it is termed herein-after, the secondary or auxiliary mechanism, that the latter is entirely controlled by the 55 former and driven directly by the same power impulses without the interposition of

other elements, such as the clock mechanism of the present type of meters.

Further, in the development of this invention, I provide an instrument in which 60 the integrating mechanism and the maximum-demand apparatus are both actuated simultaneously by the magnetic flux in a common field, and are so interrelated that, while each registers independently of the 65 other, one is dependent on the other for its retard or control against undesirable movement.

I provide also a maximum-demand instrument in which the auxiliary mechanism 70 records the maximum demand reading in direct units, that is, in watts.

With the above objects in view, the apparatus will be hereinafter fully set forth with reference to the accompanying drawings, in which—

Figure 1 is a rear elevation of the maximum demand instrument incorporated as a part of a wattmeter of well known make, parts of the latter being shown in broken 80 lines. Fig. 2 is a side elevation of the device shown in Fig. 1, Fig. 3 is a plan view, Fig. 4 is a fragmentary perspective view of a modified form of the invention, and Fig. 5 is a fragmentary perspective view of 85 certain elements, which show the invention applied to a polyphase energy meter.

With more particular reference to said drawings, in Figs. 1, 2 and 3, numerals 1 and 2 indicate parts of the electro-magnet 90 core of a wattmeter of well-known type, said core, the coils *a*, *b* and *c* and other parts not concerned directly with this invention being shown in broken lines for the sake of clearness. The main armature element 95 3 is mounted on a shaft 4 and projects into the magnetic field produced by the electro-magnet core and the shunt and series coils *a*, *b* and *c*.

The shaft 4 of the main armature element 100 3 is provided with a pinion 6 which meshes with a gear wheel 7 mounted in the frame 8, said gear wheel 7 being the first gear member of the train which constitutes the registering or integrating mechanism (not 105 shown).

Above the main frame 5, and suitably fastened thereto by screws 11, is a second frame-work, said frame-work comprising a lower plate 10 and an upper bridging plate 110 9, separated from each other by studs 12. The rear end of said plate 9 carries a bracket,

13 which is provided with an upper bearing for a secondary shaft 14 upon which an auxiliary armature element 15 is mounted, as hereinafter set forth. The lower bearing 5 of the shaft 14 is carried by a bracket 16 secured to the rear face of the electro-magnet or to the frame 5. Said bearings are adjustable and are of any suitable jeweled type.

10 The auxiliary armature element 15, which may be of any suitable form, in the present instrument is shown semi-circular in form and constructed preferably of aluminum and is so located on the shaft 14 that it projects into the magnetic field of the electro-magnet at substantially the same point as the main armature element 3, that is, between the shunt coil and the series coil. In the present instance, the auxiliary armature element 15 is located above the element 3 but it is obvious that it may equally well be located below the latter.

Near the upper end of the shaft 14, within the arch of the bracket 13, is located a hair spring 13' the inner end of which is secured to said shaft 14 and the outer end of which is secured to a projection 17 of said bracket 13. The hair spring 13' is adjusted to maintain the element 15 in normal position in the magnetic field and tends to resist the rotative motion thereof which the magnetic flux of said field tends to produce. A pointer 18, also carried by the shaft 14, projects over the top of the instrument and co-operates 35 with a scale 19 that is located at the front of the device in position to show the maximum demand in kilowatts.

The auxiliary armature element 15, when influenced by the eddy currents induced 40 therein, moves rotatively against the tension of the spring 13', if the torque be sufficiently strong. The torque may be strong enough to rotate the element but the inducing current may be only momentary, as when set up 45 by a short circuit or the sudden throwing in of a machine, and means, as hereinafter described, is provided to place a time limit on the action of the element.

A spindle 20, having bearings in the upper and lower plates 9 and 10, carries a pinion 21 which meshes with the gear wheel 7 and is driven thereby to actuate a train of gears 22, 23 and 24, through the agency of a pinion 25. Thus, the armature element 3, 55 by its connection with shaft 4 and the pinion 6 carried by the latter, is adapted to drive the above mentioned train of gears. The gear wheel 24 has mounted on its upper face near its center a pin 26. A lever 27, 60 carried at one end by a spindle 28, also having its bearings in the plates 9 and 10, is enlarged at its free end to form an elongated loop 29 which surrounds said pin 26, so that, as the gear wheel 24 revolves, pin 65 26 operates in the loop 29 to give a rotative

reciprocatory movement to said spindle 28. A double escapement lever or pallet 30 is also mounted on the spindle 28 and is so located that its teeth alternately engage the teeth of an escapement wheel 31 on the secondary shaft 14, and it will be noted that, at each half rotation of the gear 24, a tooth of the wheel 31 is freed.

It is evident from the foregoing that a time element, consisting of the train of gears 75 actuated and controlled by the shaft 4, is placed in connection with the shaft 14, whereby the movement of the element 15 is so governed that the inducing current must continue through an appreciable interval of 80 time in order to be indicated or registered by the parts 18 and 19. It follows that the indications of maximum demand will not include such momentary fluctuations as are 85 set up by short circuits and suddenly added loads.

Another spindle 32, journaled in the plates 9 and 10, carries a hair-spring 33, the free end of which is attached to a projection 34, and a pawl 35 which is kept in engagement 90 with the ratchet wheel 36 on the shaft 14. The function of the pawl 35 is to hold the shaft 14 in the position of its maximum rotative movement until such time as it is manually or otherwise released. Means for releasing said pawl is not shown because the same will preferably be carried by the instrument case and may be of any desired form.

In Fig. 4 is shown a modification of the 100 above described apparatus which may advantageously be used, especially where very compact, single-phase current meters, are desired. A frame 37 carries a bearing member 38 in which the upper end of a main shaft 39 is journaled.

The armature element 40 is supported on the shaft 39 concentrically with an auxiliary element 41. Said auxiliary element 41 is spaced above the element 40 and is supported by hanger rods 42 the upper ends of 110 which are secured to a cross-bar or head 43. A shaft or spindle 44, the upper end of which is provided with a bearing in a bracket 45, extends through the middle of, and is 115 rigidly fixed to the cross-head 43 and has its lower end supported in a bearing in the upper side of the member 38. The auxiliary element 41 is centrally apertured at 46 so that its movement may be freely independent 120 of the rotation of the element 40. It is evident that the fluxes which influence element 40 will immediately, and to the same extent, influence the element 41 but, the mounting of the two elements being entirely independent of each other, the motion of element 41 may be regulated as readily as the motion of the auxiliary element in the construction shown in Fig. 1.

In the modification shown in Fig. 5, 47 is 130

the magnet core of a polyphase meter and 48 the two main armature elements. The two auxiliary elements 49 are rigidly mounted upon the shaft 50 of the maximum-demand 5 attachment.

In the operation of the apparatus hereinbefore described, the magnetic fluxes set up in the field of the electromagnet develop the torque in the main element 3 which 10 involves the latter and sets in operation the registering or integrating apparatus. The same flux which influences element 3, is applied to the auxiliary element 15, and the shaft 14 is actuated in opposition to the 15 hair-spring 13' until the two forces are balanced, the pointer 18 moving over the scale 19 to indicate the maximum arc of movement. The rotative movement of the shaft 14 is limited, however, by the time element 20 consisting of the gear train and escapement mechanism connecting shaft 14 and main shaft 4. Since shaft 4, starts to rotate simultaneously with the shaft 14, the gear train is set in motion immediately, and the 25 escapement lever 30 begins to act on the escapement wheel 31. This acts to retard the movement of shaft 14, since the gear train is so geared down that the escapement lever, reciprocating once with each half rotation 30 of gear 24, permits the shaft 14 to move at comparatively widely separated intervals. Thus, it is necessary for the actuating torque to continue for an appreciable length of time in order to permit the shaft to operate 35 to the point where the force is balanced by the hair spring 13'. In this way, the momentary torques of short circuits and added loads are prevented from making themselves felt in the maximum-demand apparatus. By changing the ratios of the gears of the train-gear, the intervals at which the escapement operates may be varied.

When the shaft 14 moves to the limit of the force exerted, and the actuating force 45 subsides, the shaft is retained in its position of maximum movement, as hereinbefore described, by means of the pawl 35 and ratchet wheel 36, until such time as the meter is read and reset.

From the foregoing, it will be understood 50 that two mechanisms are actuated in accordance with the energy to be measured. If no means were connected between the two mechanisms one would indicate the energy that has traversed the meter and the other would indicate the power traversing the meter. Hence, if the power fluctuated, the indicating pointer 18 would indicate such fluctuations.

It is well known that no definite law has 55 been agreed upon in regard to the extent to retard the pointer 18 of the meter in order to cause it to indicate a value that will represent the demand which is most suitable for computing a customer's bill. However,

it has been determined that, if the pointer 18 is so retarded in its operation in accordance with any predetermined law, which, in this case is in accordance with the rate of energy or the power traversing the meter, 70 it will indicate a value that is not subject to rapid fluctuations which may be regarded as the desired maximum demand or the demand equivalent of the energy to be metered. That is, its indications will be substantially steady or damped and will gradually reach a value corresponding to the demand equivalent.

The operations of the complete devices constructed according to the modifications 80 shown in Figs. 4 and 5 are similar or the same as the operation of the device fully described in this specification.

I claim as my invention:

1. An electro-responsive device comprising 85 two movable members, a single means for applying similar actuating forces to the said movable members and means interposed between the two movable members whereby one of the movable members controls the operation of the other.

2. A meter comprising two armature elements, a single means for simultaneously applying similar actuating forces to the said armature elements, an indicator actuated by 95 one of the said elements and means whereby the other element controls the actuation of the said indicator.

3. In a wattmeter, the combination with 100 means for developing a magnetic field, of an integrating mechanism, an element controlled by the said magnetic field for actuating the said integrating mechanism, a maximum-demand mechanism also controlled by the said magnetic field, and an 105 indicator actuated by one mechanism and controlled by the other.

4. In a wattmeter, the combination with 110 means for developing a magnetic field, of an integrating mechanism, an element controlled by the said magnetic field for actuating the said integrating mechanism, a maximum-demand mechanism also controlled by the said magnetic field, an indicator actuated by one mechanism, and 115 means interposed between the said mechanisms whereby the indicator is controlled by the other mechanism.

5. A wattmeter comprising two movable members, a single means for applying similar actuating forces to the said movable members and means interposed between the two movable members for causing one movable member to be retarded a time interval 120 in its operation.

6. In a wattmeter, the combination with 125 means for developing a magnetic field, of an integrating element, means actuated by the magnetic field for actuating the said integrating element, an indicating element, 130

means also actuated by the magnetic field for actuating the said indicating element, and means connected en train between the said integrating element actuating means and the last mentioned means for controlling the extent of movement of the said indicating element.

7. In a wattmeter, the combination with means for developing a magnetic field, of 10 independently mounted armature elements controlled by said magnetic field, an integrating means actuated by one of said armature elements, a maximum-demand indicator actuated by another of said armature 15 elements, and a means connected en train between said armature elements, whereby the movement of said maximum-demand indicator is controlled.

8. In a wattmeter, the combination with 20 means for developing a magnetic field, of an integrating mechanism, a maximum-demand registering means, an armature in said magnetic field and connected to said integrating mechanism, a second armature also in said 25 magnetic field and connected to said maximum-demand registering means, and a time element connected en train between said armatures, whereby the movement of said second armature is controlled by the movement of the first armature.

9. In a maximum demand wattmeter, the combination with means for developing a magnetic field, of an integrating mechanism, a maximum-demand registering means, an 35 armature element geared to said integrating mechanism and located in said magnetic field, a second armature element located in said field in position to receive at least a part of the same magnetic influence as said 40 first mentioned armature element and connected to said maximum-demand registering means, a tensioned element adapted to balance the effect of the magnetic influence on said second armature element, and a time 45 element connected en train between said armature elements, whereby the former retards the action of the latter.

10. In a wattmeter, the combination with means for developing a magnetic field, of an 50 integrating mechanism, a maximum-power registering means, of an armature projecting into said magnetic field and connected to said integrating mechanism, a second armature also projecting into said magnetic 55 field and connected to said maximum-power registering means, and a time element connected en train between said armatures, and consisting of an escapement mechanism geared to the shaft of said first mentioned 60 armature element, and acting on an escapement wheel carried by the shaft of said second armature element.

11. In a wattmeter, the combination with means for developing a magnetic field, of an 65 integrating mechanism, a maximum-power

registering means, an armature projecting into said magnetic field and connected to said integrating mechanism, a second armature also projecting into said magnetic field and connected to said maximum-power 70 registering means, means for retaining said second armature in its position of maximum movement when influenced by said magnetic field, and a time element connected en train between said second armature and said first 75 armature.

12. In a wattmeter, the combination with means for developing a magnetic field, of an integrating mechanism, a maximum-power 80 registering means, an armature element geared to said integrating mechanism and projecting into said magnetic field, a second armature element projecting into said field to receive, in whole or in part, the same magnetic influence as said first mentioned armature element and connected to said maximum-power registering means, a tensioned element adapted to balance the effect of the magnetic influence upon said second armature element, means for retaining said second armature element in its position of maximum deflection, and a time element connected en train between said armature elements.

13. In a wattmeter, the combination with means for developing a magnetic field, of an integrating mechanism, a maximum-power 95 registering means, an armature element geared to said integrating mechanism and projecting into said magnetic field, a second armature element projecting into said field to receive influence from the same magnetic field as said first mentioned armature element and connected to said maximum-power registering means, a tensioned element 100 adapted to balance the effect of the magnetic influence upon said second armature element, releasable means for retaining said second armature element in its position of maximum deflection, and a time element connected en train between said armature elements.

14. A wattmeter comprising two movable members, a single means for actuating the movable members in accordance with the 115 energy traversing the wattmeter and means actuated by one of the members for causing the other member to be retarded in its operation in accordance with energy traversing the meter.

15. In a wattmeter, the combination with means for developing a magnetic field, of an integrating element, means actuated by the magnetic field for actuating the said integrating element, an indicating element, 125 means also actuated by the magnetic field for actuating the said indicating element, and means whereby the integrating element causes the indicating element to be so retarded that it will indicate a substantially 130

- steady value that is the demand equivalent of the fluctuating energy traversing the meter.
16. A wattmeter comprising two armature elements, means for simultaneously applying thereto similar actuating forces, integrating and indicating mechanisms associated respectively with said armature elements, and means whereby the integrating armature element controls the operation of the indicating mechanism.
17. A wattmeter comprising a main and an auxiliary armature element, means for simultaneously applying to said armature elements similar actuating forces, and means whereby the main armature element controls the operation of the auxiliary armature element.
18. In a wattmeter, the combination with means for developing a magnetic field, of an integrating element, means actuated by the magnetic field for actuating the said integrating element, an indicating element, means also actuated by the magnetic field for actuating the said indicating element, and means actuated by the integrating element for so controlling the indicating element that it indicates the demand equivalent of the energy traversing the meter.
19. In a wattmeter, the combination with means for developing a magnetic field, of an integrating element, means actuated by the magnetic field for actuating the said integrating element, an indicating element, means also actuated by the magnetic field for actuating the said indicating element, and means actuated by the integrating element for so increasing the time required for the indicating element to operate that its indication is substantially the demand equivalent of the energy traversing the meter.
20. In a wattmeter, the combination with means for developing a magnetic field, of an integrating element, means actuated by the magnetic field for actuating the said integrating element, an indicating element, means also actuated by the magnetic field for actuating the said indicating element, and means disposed between the two ele-
- ments whereby the indicating element is so retarded that it will indicate the demand equivalent of the energy traversing the meter.
21. An electro-responsive device comprising two movable members, a single means for applying similar actuating forces to the said movable members and means interposed between the two movable members whereby one so retards the movement of the other that a time interval is required for it to move to its final position.
22. A wattmeter comprising two movable members, a single means for applying similar actuating forces to the said movable members and means interposed between the two movable members whereby one causes the operation of the other to be delayed an interval of time.
23. A wattmeter comprising two armature elements, means for independently applying thereto similar actuating forces, integrating and indicating mechanisms associated respectively with said armature elements and means whereby one of the mechanisms controls the operation of the other.
24. In a wattmeter, the combination with means for developing a magnetic field, of an integrating mechanism, an element controlled by the said magnetic field for actuating the said integrating mechanism, a second mechanism independently controlled by the said magnetic field, and an indicator actuated by one mechanism and controlled by the other.
25. In a wattmeter, the combination with means for developing a magnetic field, of two mechanisms adapted to be simultaneously and independently actuated by the magnetic field, and an indicator actuated by one mechanism and controlled by the other.

The foregoing specification signed at Boston, Massachusetts this ninth day of March, 1912.
